JOHN N. WOODWARD, OF AURORA, ILLINOIS, ASSIGNOR TO HIMSELF AND
THOMAS ARENSER, OF SAME PLACE.

Letters Patent No. 64,731, dated May 14, 1867.

IMPROVED PAINT-BRUSH.

The Schedule referred to in these Letters Patent and making part of the same.

TO ALL WHOM IT MAY CONCERN:

Be it known that I, JOHN N. WOODWARD, of Aurora, in the county of Kane, and State of Illinois, have invented a new and useful Improvement in Paint-Brushes; and I do hereby declare that the following is a full, clear, and exact description of the same, reference being had to the annexed drawings, making part of this specification, in which—

Figure 1 is an elevation showing the shape of the band as manufactured; and

Figure 2 is a perspective view of a paint-brush with the band applied.

The same letters are employed in both figures in the indication of the same parts.

The object of this invention is the application to a paint-brush, when new, of a band, which, passing around the brush at the base of the bristles, will give additional stiffness to the bristles when long, and which may be removed when the bristles are worn short by use and no-longer require this support.

The band, as shown in fig. 1, is made in a single piece. The circular part of the band A surrounds the brush immediately below the part of the bristles which connects them with the handle of the brush, and is a flat, flexible piece of thin metal. It is connected by the neck B' with the eyes B B, which are made to slip over the handle of the brush. One of these has a tongue, C, projecting from the top, and the other has a corresponding slot cut through the neck at C'. The strap A has a notch cut in its end at D, leaving projections on each side. On the other end are corresponding narrow slits D' cut from the edge on each side. On the same end with the slits D' is a tongue, E, and at the other end a corresponding narrow slot, E'. In applying the band the strap A is bent around the bristles below their point of attachment to the handle, the handle being first passed through the eyes B. The tongue E is passed under the other end of the belt and passed outwards through the slot E', the tongues at D being passed under the plate through the slot D'. The tongue C is passed under the plate through the slot C', and the tongue E, when the band is drawn tightly around the bristles, is bent back over the plate towards its base, securely locking the band in place. The band may be withdrawn by bending the tongue E back until it is again straight, and separating the parts.

What I claim as my invention, and desire to secure by Letters Patent, is—

The band A with eyes, tongues, and slots, as described, for attachment adjustably to the outside of paint-brushes, substantially in the manner set forth.

In testimony whereof I have signed my name to this specification in the presence of two subscribing witnesses.

JOHN N. WOODWARD.
